(57) **CLAIM**

The ornamental design for a user interface for medical workstation, as shown and described.

DESCRIPTION

FIG. 1 is a perspective view of an first embodiment of a user interface for medical workstation showing our new design. FIG. 2 is a front view of the user interface for medical workstation of FIG. 1.

FIG. 3 is a back view of the user interface for medical workstation of FIG. 1.

FIG. 4 is a right-side view of the user interface for medical workstation of FIG. 1.

FIG. 5 is a left-side view of the user interface for medical workstation of FIG. 1.

FIG. 6 is a top view of the user interface for medical workstation of FIG. 1; and,

FIG. 7 is a bottom view of the user interface for medical workstation of FIG. 1.

In the drawings, the broken lines are for the purpose of illustrating environment only and form no part of the claimed design.
